UNITED STATES PATENT OFFICE.

WILLIAM HENRY MORGAN, OF ALLIANCE, OHIO.

RAILROAD-TRACK CONSTRUCTION.

1,119,623.

Specification of Letters Patent.

Patented Dec. 1, 1914.

Application filed February 20, 1914. Serial No. 829,029.

To all whom it may concern:

Be it known that I, WILLIAM H. MORGAN, a citizen of the United States, resident of Alliance, in the county of Stark and State 5 of Ohio, have invented certain new and useful Improvements in Railroad-Track Construction; and I do hereby declare the following to be a full, clear, and exact description of the invention, such as will 10 enable others skilled in the art to which it appertains to make and use the same.

My invention relates to an improvement in railroad track construction, the object being to so construct the track that the rails 15 will be supported throughout their entire length by connected girders, thereby permitting the use of smaller rails, than can safely be used on a track in which the rails are supported at intervals on the ties.

With this and other objects in view my invention consists in the parts and combinations of parts as will be more fully explained and pointed out in the claims.

In the accompanying drawings, Figure 1 25 is a perspective view of a section of a track embodying my improvement; Fig. 2 is a view in cross section through a rail and girder and showing the tie in elevation and the chair partly in elevation and partly in 30 section; Fig. 3 is a view in elevation of one of the ties; Fig. 4 is a view in perspective of the chair and Fig. 5 is a view in section showing means for insulating the rail.

1 represents the tie preferably made of 35 steel, I-shape in cross section, and each is provided with base flanges 2 wider than the top flange 3, and preferably inclined downwardly as shown in Fig. 1 so as to form a housing, under or within which the 40 ballast will pack when tamped.

Each tie is provided on its upper face with two depressed seats 4 formed by drop forging or in any other manner, and located with their centers approximately under the centers of the two rails of the track-way as shown in Fig. 2. These depressed seats 4 may have straight sides, either vertical or inclined, but I prefer to make them with a gradual curve which merges into the 50 top surface of the tie. The bottom of the seat is however slightly wider than the width of the head of a rail so as to permit the latter to rest well down toward the bottom of the depression as will be hereinafter explained.

Secured to the top flange of the tie are

the chairs 5, each of which consists of two side members 5^a, connected by two yokes 6, the latter being integral with the side members and depending at opposite sides of the tie. These chairs are located so that the side members thereof are at opposite sides of the depressed seat, and the yokes 6, extend slightly below the bottom of the seat so as not to interfere with the girder 7 which rests within said seats. Each side member of a chair consists of a base 8, end plates 9, inner wall 10 and a top shoulder 11 all formed integral. Each base plate 8 is straight on its lower face adjacent its outer end, so as to rest solidly on the flat upper face of the tie, and is thickened and curved at its inner end, so as to conform to the curvature of the side wall of the depressed seat. The end plates 9 and inner wall 10, support the top shoulder 11, which latter is slightly inclined as shown, and is provided with an upwardly projecting flange 12 which holds the girder 7, against lateral movement and prevents the rails 75 from spreading.

The chairs 5 are each provided at the side of their bases with the flanges 13, which are bent around under the top flange of the tie and lock the chairs in place.

The girders 7 are preferably old steel rails, placed head down within the depressed seat in the tie, and with the base flange 14 resting on the shoulders 11, as shown in Fig. 2. Any other form of girder will however answer the purpose, but I prefer old rails, on account not only of their cheapness, but also because of the superior quality of metal from which they are made. The girders 7 are approximately the depth of the seats from the shoulders 11, so as to approximately fill the space between the side members of the chair, and are suspended from and preferably wholly supported by the top shoulders 11 of the chairs. These girders support the rails throughout the length of the latter, except possibly at switches, and are arranged to break joints with the rails so that a joint in the rails, and a joint in the girders will not come between the same ties. The ends of the girders are connected by fish plates 16, and the ends of the rails 15 are connected by fish plates 17, and the connected rails and also the girders are restrained against vertical movement by the spring clips 18 which latter engage ribs 19 on the underside of the shoulders 11, on the

chairs, and bear adjacent the upper ends on the top edge of the flanges 12, the free upper edges of the clips overhanging the base flanges of the rails without contacting with the same, thus leaving the rails and girders loosely seated on the chairs and free to move lengthwise without opposition, and also free to move vertically a limited distance. The only pressure to which a rail is subjected other than downward, is an outward one which is taken care of by the side flanges 12 of the chair, hence there is theoretically, no tendency of the rails to tip, but as the ends of the clips overhang the base flanges of the rails and are only removed therefrom a limited distance, it will be seen that tipping to anything like a dangerous extent would be absolutely prevented by the ends of the clips. The clips shown are of spring metal sprung into place on the chair, and are carried solely by the chairs but it will be clearly evident that instead of using spring metal clips, I may use rigid stops secured to the chair and overhanging the base flange of the rail, hence I would have it understood that my invention herein shown, is just as well adapted for use with rigid overhanging stops as it is for the U-shape spring clips herein shown and described.

With the construction above described, wherein the rails are supported on connected girders, the load is distributed equally on and between all the ties, and by using old rails, instead of built up girders, all objection to riveted structure is avoided. By supporting the rails on suspended girders, a lighter rail can do the work of a much heavier rail that is supported at intervals on ties. The larger the rail the softer the head thereof. This is due to the inability to work it sufficiently to harden it. With these improvements smaller rails supported throughout their lengths and at their ends, can be safely used with the heavy rolling stock that is now rapidly coming into use, and which could not be used if they were supported only at intervals.

By the use of the stringers in conjunction with the cross ties, I distribute the rolling load very uniformly over the cross ties; considerably reduce the pressure per square foot between the ties and the ballast and also reduce the cost of maintaining the road bed owing to the fact that less re-tamping will be required. This is very essential as there must be at least twelve inches between ties, (which are approximately eight inches base widths) for tamping, and as the ties are about twenty inches apart from center to center, there is no room for additional ties.

By the use of the stringers the load will be distributed over a greater number of ties, and as the rails themselves are not of strength sufficient to distribute the load, the

use of old or new rails in the form of stringers with the rails resting on top of the latter, form in effect a bridge for carrying the load over and onto several ties.

While I prefer to provide the ties with 70 depressed seats and have so shown them, the depression may be dispensed with and the chairs constructed to support the stringers above the top surface of the ties.

When it is necessary to insulate the rails 75 from the ties, it may be conveniently done as shown in Fig. 5, by providing the chair with a removable shoulder 20 and flange 21, and interposing insulating material 22 between said shoulder and flange and the chair 80 proper, and also interposing insulating material 23 between the chair and the armor plate 24 against which the lower end of the spring clip bears.

It is evident that many slight changes 85 might be resorted to in the relative arrangement of parts shown and described without departing from the spirit and scope of my invention. Hence I would have it understood that I do not wish to confine myself 90 to the exact construction and arrangement of parts shown and described, but

Having fully described my invention what I claim as new and desire to secure by Letters-Patent, is:—

1. In railroad track construction, the combination of ties each having depressed seats near its ends, girders suspended within said depressions, rails resting on the top faces of the girders and means for preventing vertical displacement of the rails.

2. In railroad track construction, the combination of ties, chairs resting on the ties, connected girders carried by the chairs, rails resting on the tops of the girders and means 100 for preventing vertical displacement of the rails.

3. In railroad track construction, the combination of ties, chairs thereon, girders suspended within the chairs, rails resting on the 110 girders and means for preventing accidental displacement of the rails.

4. In railroad track construction, the combination of ties, a chair on the tie adjacent each end, a girder suspended by and within 115 the chair, a rail resting on each girder and means for preventing vertical displacement of the rails and girders.

5. In railroad track construction, the combination of metal ties each having a recess 120 in its top adjacent each end, chairs secured to the ties adjacent the recesses, girders within said recesses and suspended from the chairs, rails on said girders, and means for locking the rails against vertical displacement.

6. In railroad track construction, the combination with metal ties each having a recess 130 in its top near each end, two chairs on each tie, each chair secured to a tie adjacent a re-

cess, I-shaped girders within said recesses and suspended from the chairs, rails loose on said girders, and means carried by the chairs for preventing vertical displacement 5 of the rails, the said rails being unrestrained against longitudinal movement.

7. In railroad track construction, the combination of metal ties, chairs secured to the ties adjacent the ends thereof, each chair 10 composed of two side members connected by depending yokes, girders suspended from and between said side members, rails resting on the girders, and means for securing the rails to the chairs.

15 8. In railroad track construction, the combination of I-shaped metal ties each having a recess near each end, chairs, each composed of two side members the latter being located on opposite sides of a recess in the tie, and depending yokes integral with and connecting the side members, I-shaped girders suspended from the chairs, and over said depressed seats, rails resting on the girders and means for securing the rails against vertical displacement.

9. In railroad track construction, the combination with metal ties, each having a recess in its upper surface near each end, two chairs secured to each tie adjacent the recesses therein, each chair composed of two side members connected by depending yokes the latter resting on opposite sides of the tie, I-shaped girders loosely suspended from said chairs and between the two members 35 thereof, rails loosely seated on said girders and means for preventing vertical displacement of the rails.

10. In railroad track construction, the combination of metal ties recessed on their top faces near their ends, chairs secured to the ties, each chair composed of two side members and yokes connecting the latter, girders composed of connected rails, inverted and suspended from supports on the side members of the chairs, rails resting loosely on said girders and means for preventing vertical displacement of the rails.

11. In railroad track construction, the combination of metal ties, two chairs secured to each tie, each chair composed of two side members each of the latter having a shoulder and an upwardly projecting flange, depending yokes connecting said side

members, I-shaped girders suspended from said shoulders, rails supported throughout 55 their length on the girders and means for preventing vertical displacement of the rails.

12. In railroad track construction, the combination of metal ties, two chairs secured to each, each chair composed of two 60 side members each of the latter having a shoulder and an upwardly projecting flange, insulating means between said shoulder and flange and the body portion of the side members, depending yokes connecting said side 65 members, I-shaped girders between said side members and suspended from the seats on the latter, rails loosely resting on the girders and means for securing the rails against vertical displacement.

13. The combination of metal ties, chairs secured to the ties, connected girders seated within the chairs and confined laterally by the latter, and rails resting on the top of the girders.

14. In railroad track construction, the combination of metal ties, two chairs on each tie, I-shaped girders carried by said chairs, rails loose on the girders, and means carried by the chairs for preventing vertical displacement of the rails, the said rails being unrestrained against longitudinal movement.

15. In railroad track construction, the combination of metal ties, chairs secured thereto, each chair composed of two side 85 members, yokes integral with and connecting said members, I-shaped girders suspended from and between the members of said chairs, rails resting on the girders and means for locking the rails against accidental displacement.

16. In railroad track construction, the combination of metal ties, chairs secured to the same, girders composed of connected rails inverted and suspended from supports 95 on said chairs, rails resting on said girders and means for preventing displacement of the rails.

In testimony whereof, I have signed this specification in the presence of two subscribing witnesses.

WILLIAM HENRY MORGAN.
